UNITED STATES PATENT OFFICE

CORNELIUS B. WATSON AND AUDLEY E. HARNSBERGER, OF CHICAGO, ILLINOIS, ASSIGNORS TO THE PURE OIL COMPANY, OF CHICAGO, ILLINOIS, A CORPORATION OF OHIO

OIL VAPORIZER AND CONVERTER

Application filed February 21, 1928. Serial No. 256,044.

The present invention relates to a combined oil vaporizer and converter wherein both the vaporizing and converting sections of the furnace are arranged within a single setting or housing and wherein is provided a novel arrangement of the oil vaporizing tubes and the converting tubes of the furnace for the purpose of obtaining the maximum benefit of the heat developed within the furnace.

The present invention provides an oil heater or furnace which is particularly applicable to vapor phase methods of converting relatively high boiling hydrocarbons into hydrocarbons of lower boiling point. In most vapor phase systems of oil conversion the vapors while undergoing decomposition are heated to a temperature in excess of 500° cent. It is therefore necessary to provide a highly efficient type of heater or furnace for the purpose of securing the necessary operating temperatures and at the same time to make the most effective use of the heat generated so that the system may be operated economically from a standpoint of fuel consumption.

In accordance with this the present invention provides a heater or furnace which is so constructed that the fire gases while at high temperature will sweep the vapor conducting tubes comprising the converting zone of the system in order that such tubes will be heated to procure the necessary conversion reaction in the oil vapors passing through the tubes. Further, the furnace is so constructed that after the fire gases have swept by the tubes of the converting zone such gases will then be conducted to a second section of the furnace which contains a plurality of tubes in which the oil under treatment is vaporized preparatory to its introduction into the converting tubes. By this arrangement the heat developed within the furnace is efficiently utilized in the performing of necessary operations so that when the fire gases are discharged from the furnace the major portion of the heat value thereof will have been extracted and economically employed in the operation of the system.

Another object of the invention resides in forming the converting sections of the furnace so as to provide a combustion chamber, a primary tube chamber and a secondary tube chamber, the said chambers being separated by an intervening bridge wall. By this arrangement the tubes in the primary chamber are subjected to both convection and radiant heat developed within the combustion chamber, while the tubes in the secondary chamber are subjected to convection heat alone. This arrangement has been found to be distinctly beneficial in preventing the formation of coke or the liberation of free carbon in the oil vapor entrance tubes of the converter sections. Oil vapors at a temperature of approximately 650° Fah. enter the inlet passes of the converter tubes and it has been found that by suddenly and substantially instantaneously raising the temperature of these oil vapors from 650° Fah. to a temperature in excess of 1000° Fah. there will be little or no accumulation of obstructing or clogging carbon deposit in the inlet passes of the converter tubes. For this reason such inlet passes are disposed in the primary chamber of the heater so as to be subjected to the radiant heat developed within the combustion chamber of the furnace. Since the rate of heat transfer by radiation is proportional to the fourth power of the difference between the absolute temperature of the radiating and absorbing structures, it follows that; the temperature of the vapors entering the initial passes of the converter tubes is rapidly raised to a conversion temperature in excess of 1000° Fah. When the conversion temperatures are attained the oil vapors then pass into the tubes situated within the secondary chamber, where the conversion temperatures are maintained for a desired period of time.

For a further understanding of the invention reference is to be had to the following description and the accompanying drawing wherein the figure is a vertical sectional view taken through an oil heating furnace formed in accordance with the present invention.

Referring more particularly to the drawing the numeral 1 designates a furnace or heater particularly adapted for vapor phase methods of oil conversion. The furnace is formed to include the usual setting or walls which are formed from a refractory material capable of withstanding the relatively high temperatures developed within the furnace. Broadly, the furnace is formed to include what may be termed a converting section 2 and a vaporizing section 3, the sections 2 and 3 being connected by means of a flue or passageway 4, permitting of the travel of the fire or furnace gases from the converting section, where the heat is generated, into the vaporizing section.

The converting section of the furnace includes an upright bridge 5, formed to include side walls 6 and an arched top 7. The bridge divides the interior of the converting section into primary and secondary chambers 8 and 9 respectively which are united by a passageway formed between the top of the bridge and the top wall 10 of the setting. The front wall of the setting is offset to produce a horizontally extending portion 11 which produces the top wall of a Dutch oven or combustion chamber 12 with which the primary chamber is in direct communication.

Formed in the wall 6 of the bridge which defines the back of the combustion chamber is an air passageway 13 which terminates in a horizontally extending communicating passageway 14 which is formed in the bottom of the chamber 12. The passageway 14 terminates immediately adjacent to a burner structure 15, utilizing either gaseous or liquid fuel. Air enters the passageways 13 and 14 from any suitable source and is preheated by reason of the temperature of the walls surrounding the same. This preheated air is then delivered into the combustion chamber where it actively intermingles with the gaseous or liquid fuel used for the purpose of promoting and facilitating combustion. It will be understood that one or more burners 15 may be employed.

Arranged horizontally within the chamber 8 is the inlet pass of a row of converting tubes 16, the outer ends of which being extended through the front wall of the setting and connected with a header 17. The tubes 16 pass through the bridge 5 and are connected with a second bank of similarly arranged tubes 18, which are situated within the secondary chamber 9. It will be understood that the ends of the tubes comprising the bank 18 are connected with headers or return bends 20 at their ends for the purpose of permitting of the uninterrupted circulation of oil vapor first through the tubes 16 and thence through the tubes comprising the bank 18.

After the furnaces gases within the con-

verter section have swept the tubes 18, such gases are then conducted by way of the conduit or flue 4 to the vaporizing section of the furnace. If desired, the flow of the gases through the flue may be regulated by means of an adjustable damper 21. The vaporizing section includes an internal chamber formed by the setting of the furnace wherein is disposed a vertical wall 22 which divides the vaporizing section into a gas circulating chamber 23 and a tube chamber 24. The bottom of the chamber 23 includes a baffle wall 25 arranged adjacent to the outlet of the flue 4. Behind the baffle 25 there is situated a burner 26 which may be used, if necessary, to raise the temperature of the furnace gases entering the chamber 23. The burner 26 is in the nature of an auxiliary appliance and need not be continuously operated.

After passing through the circulating chamber 23, the furnace gases then flow as indicated by the arrows, in a downward direction, sweeping through a bank of vaporizing tubes 27 arranged within the chamber 24. After sweeping the tubes 27 the furnace gases then in a relatively cooled state pass from the furnace by way of the stack outlet 28, the latter being arranged at the bottom of the chamber 24.

In the operation of the system the oil stock is forced into the bottom tubes of the bank 27 and circulates upwardly through these tubes where, by reason of the furnace temperatures, which are approximately 1800° Fah., the oil is vaporized and brought to a temperature of approximately 650° Fah. The oil and oil vapors then leaving the outlet of the tubes 27 pass by way of a pipe line 29 to a separator 30, disposed extraneously of the furnace. Within this separator superheated steam may be introduced as at 31. The introduction of this steam is, however, optional, since in certain vapor phase systems superheated steam is not employed at the time of conversion. Within the separator there takes place a rough or preliminary separation of the oil fractions. The heavier or liquid fractions which have not vaporized at a temperature of about 650° Fah. collect in the bottom of the separator and are withdrawn from the system by way of the pipe line 32. The lighter or vaporized fractions, however, with the superheated steam, if the latter is used, pass overhead from the separator 30 and by means of a pipe line 33 are introduced into the inlet header 17 of the entrance tube 16. The oil vapors at the time when they are initially introduced into the tubes 16 are at a temperature of approximately 600 to 650° Fah. and then upon being circulated through the tubes 16 the vapors are subjected to the intense or high temperatures developed within the primary chamber 8, utilizing to a

very large extent the radiant heat developed within this section of the furnace. This quickly brings the temperature of the oil and oil vapors to a critical conversion temperature in excess of 1000° Fah. and in operation the rise in temperature may be said to be instantaneous. By securing this sudden rise in temperature little or no carbon formation will accumulate on the inner walls 10 of the tubes 16. The oil vapors then circulate into the final bank of tubes 18 arranged in the convection heat chamber 9, where the oil vapor is maintained for a desired period of time at such critical temperatures 15 to secure the desired reaction for the purpose of breaking down the oil into compounds suitable for use as a motor fuel. Following discharge from the bank of tubes 18, the oil vapors are then condensed and 20 fractionally separated in any desired manner customary in refining operations.

The furnace lends itself to operations without recirculation of the flue gases, air being drawn through the rear combustion 25 space wall and under the setting, thereby preheating the air and giving a short flame in the Dutch oven to prevent flame impingement on the tubes 16. However, little difficulty has been encountered in the matter 30 of tube construction, since the coolest vapors enter above the high temperature furnace zone and also by the fact that these tubes may be made of special materials to resist the destructive action of the high temperatures. The furnace has the advantage of 35 being extremely compact and easy to control. It will be understood that its capacity may be varied by placing any desired number of tubes in parallel horizontal rows and 40 by placing any number of burners across the firing front.

What is claimed is:

1. In an oil heater, a furnace including a setting, a bridge wall situated within said setting and dividing the latter into primary and secondary chambers, a burner situated within said setting and so positioned as to effect upward movement of the furnace gases through the primary chamber and downward movement of said furnace gases in the secondary chamber, there being a gas outlet provided at the lower part of the secondary chamber, a single horizontal row of heat absorbing tubes arranged openly in the primary chamber and disposed below the top of said bridge wall, a bank of tubes arranged horizontally in said secondary chamber and in direct communication with the row of tubes in said primary chamber, and means 50 for effecting travel of the oil and oil vapor through the bank of tubes in the secondary chamber in a direction substantially parallel or concurrent with the flow of furnace gases through the secondary chamber.

2. In an oil furnace, a setting formed to

include conversion and vaporizing sections, said conversion section being formed to include communicating primary and secondary chambers, a bridge wall separating the primary and secondary chambers and spaced 70 from the roof of said setting to admit of open communication between said chambers contiguous to the roof of the setting, a heat generator arranged within said setting and disposed to effect upward travel of the gases 75 of combustion through the primary chamber and approximately downward travel of said gases through the secondary chamber, oil vapor conducting tubes arranged openly 80 in both the primary and secondary chambers, a conduit connecting the lower portion of said secondary chamber with said vaporizing section, a bridge wall in said vaporizing section and dividing the latter into combustion and heating zones, means for passing 85 oil and oil vapor upwardly through the tubes in said heating zone in counter-current or opposed relationship to the descending heating gases, and means for passing oil vapor through the tubes in the secondary 90 chamber of said conversion section in a substantially downward direction parallel with the flow of combustion gases through the secondary chamber.

3. In an oil heater, a furnace including a 95 setting, a bridge wall situated within said setting dividing the latter into primary and secondary chambers, a burner situated within said setting to effect substantially upward movement of the furnace gases through the 100 primary chamber and downward movement of such gases in the secondary chamber, there being a gas outlet provided in communicating relationship with the lower part of the secondary chamber, a horizontal row 105 of heat absorbing tubes arranged openly in the primary chamber, said tubes being spaced from the roof of said chamber and supported by the upper portion of said bridge wall, a communicating second bank 110 of tubes arranged in said secondary chamber, and means for effecting travel of the oil and oil vapor through the bank of tubes in the secondary chamber in a direction substantially parallel or concurrent with the 115 flow of furnace gases through the secondary chamber.

4. In an oil heater, a furnace including a setting, a bridge wall situated within said setting and dividing the latter into primary and secondary chambers, the upper end of said bridge wall being spaced from the roof of the setting, burners arranged in the lower part of said primary chamber to effect substantially upward movement of furnace 120 gases through the primary chamber and substantially downward movement of the furnace gases through the secondary chamber, there being a gas outlet provided in communication with the lower part of the 125

secondary chamber, a single horizontal row of relatively spaced longitudinally extending tubes supported at their ends in connection with the front and back walls of said setting and having their intermediate portions supported by said bridge wall, and a plurality of horizontally arranged tubes disposed only in said secondary chamber in communication with and below said first named tubes, the lower tubes in said secondary chamber having their ends supported in connection with the rear wall of said setting and said bridge wall.

In testimony whereof we affix our signatures.
